INSECT TRAP OR SIMILAR ARTICLE

John S. Levey, 12160 Victory Blvd.,
Los Angeles, Calif. 91606

Filed Jan. 19, 1970, Ser. No. 20,984

Term of patent 14 years

Int. Cl. D22—09

U.S. Cl. D22—19

FIG. 1 is a perspective view of an insect trap or similar article, showing my new design;

FIG. 2 is a perspective view of the design of FIG. 1 wherein the sidewalls have circular apertures therein in combination with the floral pattern;

FIG. 3 is a top plan view thereof; and

FIG. 4 is a bottom plan view thereof.

I claim:

The ornamental design for an insect trap or similar article, substantially as shown and described.
